UNITED STATES PATENT OFFICE.

MARTIN ATHANASIUS KUEHN, OF WILKES-BARRE, AND BENJAMIN F. BAIN, OF PITTSBURGH, PENNSYLVANIA; SAID KUEHN ASSIGNOR TO SAID BAIN.

GAME.

Application filed January 24, 1924. Serial No. 688,252.

To all whom it may concern:

Be it known that we, MARTIN A. KUEHN and BENJAMIN F. BAIN, citizens of the United States, residing at Wilkes-Barre and N. S. Pittsburgh, in the counties of Luzerne and Allegheny, respectively, and State of Pennsylvania, have invented certain new and useful Improvements in Games, of which the following is a specification, reference being had therein to the accompanying drawing.

This invention relates to games, and more particularly to a checker type of game, wherein opposing men are movable over the playing surface and wherein an opponent's man or men may be jumped and thus eliminated from further participation.

One of the objects of the invention is to provide a game which will not only be interesting and afford considerable amusement to the participants, but one which requires considerable exercise of brain power in order to accomplish the defeat of the opposing player.

Another object of the invention is to provide a checker type of game in which the opposing men are moved in accordance with chance devices.

Still another object of the invention is the provision of a checker type of game in which opposing men are moved in accordance with indications on chance devices, and in which the chance devices also control certain hazards in such manner that either your own or your opponent's men may be eliminated.

Further objects of the invention will appear as the following specific description is read in connection with the accompanying drawing which forms a part of this application; and in which—

Figure 1 is a plane view of the game board;

Figure 2 is a detail section taken through one of the chance controlled devices; and

Figure 3 shows an elevation of two of the playing men employed.

In the preferred embodiment of the present invention we make the playing board of a single sheet of metal with the marginal edges rolled to produce a reinforcing margin. The board is generally indicated at 1 and the reinforced margin at 2. It must be understood, however, that this playing

board can be constructed of various materials and a raised reinforced marginal edge provided in any suitable manner without departing in any way from the spirit or scope of the invention. As at present designed the board has on one face thereof indicia denoting various positions in the playing section and other indicia which will be herein-after described. The opposite side of the board which has not been shown may contain a checker board surface for playing checkers or chess, and the men employed in playing the game of the present invention may be also utilized if desired in the play of these latter two games.

As shown in Figure 1 the board comprises a center or playing section 3 and oppositely disposed marginal or reserve sections 4. At one side of each reserve section there is placed indicia denoting a fort generally indicated at 5. These forts on the board are positioned in diagonally opposite corners and each contains as a part of its paraphernalia, cannon 6 and 7 hereinafter termed the right and left guns, and also indicia denoting a source of electrical energy such as a generator 8. Within each fort is a chance device comprising a dial 9 having various marginal spaces 10, 11, 12 and 13, the first ones of which have numerals therein running from 1 to 6. The space 11 in each dial is located directly adjacent the indication of the generator and contains the words "Charged wire." The spaces 12 and 13 are located directly adjacent the right and left guns 6 and 7 and contain the words "Right gun"—"Left gun." Other spaces 14 in the dial each contain the word "Fill" the purpose of which will be herein-after described.

The playing section, broadly speaking, comprises three parts, the starting points or positions indicated at 15 and 16 and the center playing positions generally indicated at 17. The positions 15 and 16 are each six in number and are for the purpose of initially holding the first line of men at the start of the game. These positions are distinguished from those of the playing position 17 by being colored differently from the playing positions. Any distinguishing colors may of course be employed, but we prefer, as shown, to make the starting positions 15 and 16 black, while the playing positions are colored green. The back-

ground of the board may be made any suitable color, but preferably one which will not be calculated to hurt the eyes of the players.

5 As shown in Figure 1 the playing positions are arranged in rows with the positions of one row staggered with relation to the positions in the adjoining rows, and are in effect coupled together diagonally across the 10 board by the similarly colored dashes 18, which are provided to generally indicate the line of movement of the men, which in the present embodiment is in the same manner as are made in playing checkers, viz: 15 diagonally forward in either direction across the board. This game, however, unlike "crowned" men in checkers, permits no retrograde movements.

Leading across the playing section 3 and 20 touching certain of the positions or spaces 17 are lines 19 and 20 which extend from each gun 6 and 7 and indicate the travel of a shot from such gun. Also leading off 25 from the controlling switch 20 of the generator is a line 21 indicating a wire which is conducted throughout its path in zigzag form to generally indicate a charged wire. This wire touches certain of the positions 17 and passes between other of said 30 positions 17.

Each fort is provided with similar paraphernalia and the shot lines 19 and 20 extend across each other at points approximately midway across the playing section. The 35 charged wire from each fort circles around and returns to the switch at such fort, as shown in Figure 1, and leaves a central uninterrupted space in the approximate center of the playing section.

40 Each dial is provided with a pointer 22 pivoted in the center of the dial upon a hollow rivet 23, which extends through the board 1 as shown in Figure 2.

45 At 24 and 25 we have shown playing men utilized by the players of the game. These men are differently colored as shown so that they may be readily distinguished. As shown, they are in the form of soldiers, but may be of any other suitable form desired.

50 In playing the game each player places six men upon the spaces of starting position 15, and his six additional men which are herein-after known as reserves are placed in the reserve space 4 for further use. The player 55 who then begins the game spins the pointer and if the same stops upon one of the numeral sections he moves the number of men indicated one position. For instance, if the pointer stopped upon the section having the numeral 3 therein, he could move three men each one position or from the starting position 15 to the next adjoining playing position 17 in a diagonal direction. When his 60 opponent's turn came he would spin his pointer and if by chance it rested upon a

numerical section he would be move that number of men indicated one position each. This is followed out during the playing of the game, it being understood that the first player to get a man in his opponent's starting line is to be considered the winner. 70

A player may also win by taking all of his opponent's men either by elimination, by jumping or by the hazards controlled by his chance device. 75

In order that the operation of the game may be more completely described, we shall indicate the players as A and B. If the player A has moved his men or certain of them where they occupy spaces touched by the charged wire 21 or by the shot lines 19 or 20 from his opponent's fort and his opponent then spins the pointer at his station so that it comes to rest upon either of the spaces 11, 12 or 13, those A men which are 80 on positions touched by either the charged wire from the fort B or the shot lines from said fort will be eliminated from further play and will be taken by player B. In addition to moving in such manner as to avoid the hazards controlled by the opponent's chance device the player should also move to get in position to eliminate his opponent's men by jumping. Jumping can occur in 85 the same manner as in checkers, that is, provided opponent's man is immediately adjoining and there is a vacant playing space just beyond his opponent's man. When more than one man is thus in a line for 90 jumping, all may be jumped and removed from the board. There must, however, be only one vacant circle between each man and one just beyond the last man where the jumper may touch or stop. 95

If after any one or more of men have been 100 moved from the starting sections 15 or 16 either player operates his chance device so that the pointer rests upon one of the fill sections, he may bring up as many reserves 105 as he has empty spaces within the sections 110 15 or 16.

From the foregoing it can be readily seen that while a player may use considerable acumen in moving his men, that a number of set backs can be encountered through the 115 operation of the chance devices, thus affording a large number of thrills and disappointments in the playing of the game.

We claim:

1. In game apparatus, a board having a 120 playing section and a reserve section, chance controlled devices, and a plurality of men movable collectively or individually in accordance with indications on the chance controlled devices over the playing section 125 and from the reserve section to the playing section.

2. In game apparatus, a board having a 130 playing section provided with indicia denoting positions or stations, and chance con-

trolled hazards affecting certain of said positions, and opposing men movable by chance for capturing opponent's men.

3. A checker type game having a playing section, and opposing men movable thereover and chance controlled hazards affecting certain of the positions in the playing section.

4. In a game apparatus, a board having a playing section provided with indicia denoting positions or stations, opposing starting stations, and a chance controlled device for each station operable to denote moves on the playing section and into the starting section.

5. A checker type of game having a playing section provided with indicia denoting positions or stations, hazard indicia touching certain of said stations, and chance controlled devices effecting the operation of said hazards.

6. In a checker type of game, a board having a playing section provided with indicia denoting positions or stations, hazard indicia touching certain of said positions,

separate controlling stations for said hazard indicia, and chance control devices for effecting the operation of said hazard indicia.

7. In a checker type of game, a board having a playing section provided with indicia denoting positions or stations, hazard indicia touching certain of said positions. separate controlling stations for said hazard indicia, opposing starting stations, a plurality of men operating from each starting station, and chance control devices controlling the movement of said men and effecting the operation of said hazard indicia. 30 35
